DISPLAY STAND FOR MERCHANDISE

Lawrence W. Patterson, 1420 W. 5th St., Santa Ana, Calif.

Filed Sept. 20, 1960, Ser. No. 62,207

Term of patent 14 years

(Cl. D80—10)

FIG. 1 is a front perspective view taken from the top and one side of a display stand for merchandise embodying my new design; and

FIG. 2 is a rear perspective view thereof taken from the bottom and one side.

It is to be understood that the cross wires forming the several shelves, broken away for convenience of illustration, are continuous throughout each of said shelves.

I claim:

The ornamental design for a display stand for merchandise, as shown and described.
